UNITED STATES PATENT OFFICE.

CONRAD LUTTROPP, OF STOCKHOLM, SWEDEN, ASSIGNOR OF ONE-HALF TO ANDERS LINDAHL, OF STOCKHOLM, SWEDEN.

CALCULATING MACHINE.

Original application filed August 13, 1923, Serial No. 657,148, and in Sweden August 14, 1922. Divided and this application filed April 22, 1925. Serial No. 25,090.

This invention relates to calculating machines of the kind in which the main counting register is located in a traveling carriage and more especially to an improved tabulator for moving the carriage step by step in either direction.

The improved means for moving the carriage step by step comprises a rack secured to the carriage, a pinion engaged by said rack and loosely journaled on a pin in the frame of the machine, two ratchet wheels secured to said pinion and having teeth directed in opposite directions, two swingable levers journaled coaxially with the pinion, a ratchet carried by each of said levers and means for bringing either of said ratchets into operative engagement with one of the toothed wheels for rotating the pinion while the other ratchet is brought into engagement with the other toothed wheel for limiting the rotation of the pinion.

In the accompanying drawings I have shown one embodiment of my invention. Fig. 1 shows a partially sectional side-view 25 of a calculating machine having the improved tabulator mechanism for moving the carriage. Fig. 2 is a front view of the tabulator of the carriage. Fig. 3 shows a detail view of the ratchet wheels of the tabulator. Fig. 4 is a plan of the tabulator. Fig. 5 is a side view of the tabulator and one of its two operating keys. Fig. 6 is a detail view of some parts of the tabulator. Fig. 7 is a front view of other parts of the gear between 35 the tabulator and its two keys. Fig. 8 shows a detail sectional view of the releasing handle of the carriage taken on the line *a—a* in Fig. 7.

Referring now to the drawings, A is the carriage which at the top is provided with rollers 1 which run on a guiding rod 2 in the machine frame, and in the lower part with a guiding rod 3 which is guided by rollers 4 journaled in the machine frame (Fig. 1). Secured to the machine frame is a catch bar 5 in which at equal distances, corresponding to the distances between the numeral wheels in the carriage, notches 6 are provided and engaged by a spring-actuated catch 7 journaled on the carriage. Said catch has a handle 8 for releasing it by hand, if desired. At the bottom of the carriage a rack 9 is secured. Said rack is engaged by a pinion 11 loosely mounted on a pin 10 se-

cured in the frame of the machine and rigidly connected with two toothed wheels 12 and 13 journaled on the same pin (Figs. 3, 4 and 5), said wheels having teeth directed in opposite directions. In the planes of said toothed wheels 12, 13 and at opposite sides 55 thereof are provided spring-actuated ratchets 14 and 15 respectively, said ratchets being journaled on levers 16 and 17 respectively which latter are journaled on the pin 10. Between the lower ends of 60 the levers 16 and 17 a compressed spring 18 is provided, said spring tending to hold projections 19 and 20 on the one arm of 65 said levers 16 and 17 respectively in engagement with corresponding guiding pins 21 and 22 respectively secured in the front 70 plate 23 of the machine frame. The levers 16 and 17 carry also screw pins 24 and 25 respectively the projecting ends of which are guided by slots 26 and 27 respectively in 75 vertically movable slides 28 and 29 respectively. The other arms of the levers 16 and 17 are angular and form stops 30 and 31 respectively for the ratchets 15 and 14 respectively. The slides 28 and 29 are provided 80 at the lower portion with oblique portions 32 and 33 respectively. Said portions are engaged by pins 34 and 35 respectively each supported by one arm of bell crank 85 levers 36 and 37 respectively, which levers are rigidly secured to a shaft 38 journaled on the frame plate 23. The other arms of 90 said bell crank levers are connected by means of links 39 and 40 respectively with a releasing yoke 41 (Figs. 7 and 8) journaled 95 in the frame plate 23 below the catch 7. The slides 28 and 29 are connected by means of pins 42 and 43 respectively with bell crank 100 levers 44 and 45 respectively, said levers being connected by means of links 46 and 47 respectively with other bell crank levers 48 and 49 respectively which are connected with the keys 50 and 51 respectively. The slides 28 and 29 are provided at the top with pins 52 and 53 respectively engaging the rear 105 sides of the ratchets 14 and 15 respectively.

The operation of the tabulator for moving the carriage is as follows.

If for instance the carriage is to be moved to the right the key 50 is depressed causing 105 the slide 28 to be drawn downwards and the oblique portion 32 to operate the pin 34 so that the bell crank lever 36 is turned and by

means of the link 39 raises the yoke 41 which latter lifts the catch 7 out of engagement with the locking bar 5 whereby the carriage is released. Furthermore, the pin 52 presses 5 the ratchet 14 into engagement with the corresponding ratchet wheel 12 which is rotated together with the pinion 11 so that the carriage is moved to the right as soon as the slide 28 during the continued downward 10 movement rotates the lever 16 by means of the screw pin 24. When the lever 16 is rotated its projection 31 also operates the other ratchet 15 so that the latter engages its corresponding ratchet wheel 13 and limits the 15 movement exactly to one step corresponding to the distance between the successive numeral wheels in the carriage. When the key 50 then is released the slide 28 returns to its normal position and the ratchets 14 and 20 15 are brought out of engagement with the ratchet wheels 12 and 13 respectively. At the same time the catch 7 engages a notch 6 of the locking bar 5 so that the carriage will be locked in the new position. For moving 25 the carriage to the left the key 51 is depressed thus causing the slide 29 and its cooperating parts to be operated in a similar manner to that above described.

As the ratchets 14 and 15 in their normal 30 positions are out of engagement with the ratchet wheels 12 and 13 respectively the carriage can be released by depressing the handle 8 of the catch 7 by hand whereupon the carriage can be moved to the right or to 35 the left any desired number of steps.

What I claim is:

1. In a calculating machine having a traveling carriage, a device for moving the carriage step by step in either direction comprising 40 a rack secured to the carriage, a pinion engaged by said rack, two ratchet wheels secured to said pinion and having teeth directed in opposite directions, ratchets for cooperation with said ratchet wheels, two

swingable levers journalled coaxially with 45 the pinion and each carrying one of said ratchets, and means for bringing either of said ratchets into operative engagement with its corresponding ratchet wheel for rotating the pinion while the other ratchet is brought 50 into engagement with the other ratchet wheel for limiting the rotation of the pinion.

2. In a calculating machine having a traveling carriage, a device for moving the carriage step by step in either direction, comprising 55 a rack secured to the carriage, a pinion journalled on a rigid pin, two ratchet wheels secured to said pinion and having oppositely directed teeth, ratchets for cooperation with said ratchet wheels, two levers 60 journalled co-axially with the pinion and each carrying one of said ratchets, key-operated slides adapted to operate each one of said levers and its ratchet for bringing the latter into engagement with its ratchet 65 wheel, and a projection on each lever adapted to operate the ratchet of the other lever so as to cause it to engage its ratchet wheel for limiting the rotation of the pinion.

3. In a calculating machine having a traveling carriage, a device for moving the carriage step by step in either direction comprising 70 a rack secured to the carriage, a pinion journalled on a rigid pin, two ratchet wheels secured to said pinion and having 75 oppositely directed teeth, ratchets for cooperation with said ratchet wheels, two levers journalled coaxially with the pinion and each carrying one of said ratchets, a notched locking bar, a catch provided on the carriage 80 and normally engaging said locking bar, and key-operated slides adapted to release said catch and to operate each one of said levers and its ratchet for bringing the latter into engagement with its ratchet wheel. 85

In testimony whereof I have signed my name.

CONRAD LUTTROPP.
